UNITED STATES PATENT OFFICE.

ROBERT M. DIXON, OF EAST ORANGE, NEW JERSEY, ASSIGNOR, BY MESNE ASSIGNMENTS, TO STANDARD HEAT AND VENTILATION COMPANY, INC., OF NEW YORK, N. Y., A CORPORATION OF NEW YORK.

HEATER FOR WATER-CIRCULATING SYSTEMS.

1,055,725.

Specification of Letters Patent. Patented Mar. 11, 1913.

Application filed April 24, 1907. Serial No. 369,907.

To all whom it may concern:

Be it known that I, ROBERT M. DIXON, residing at East Orange, in the county of Essex and State of New Jersey, have invented certain new and useful Improvements in Heaters for Water-Circulating Systems, of which the following is a full, clear, and exact description, such as will enable others skilled in the art to which it appertains to make and use the same.

My invention relates to heating apparatus, and more especially to a heater for a water circulating system.

One of the objects of my invention is to provide an improved steam heater for a water circulating system which will automatically control the discharge of the steam and the water of condensation.

Another object thereof is to provide a novel form of thermostatic regulating device for a heater of the above type whereby the whole apparatus, while automatically regulated, is self-contained.

A further object is to provide an automatically regulated heater for a water circulating system wherein the danger of freezing is substantially eliminated.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings, wherein is illustrated one of the various possible embodiments of my invention, Figure 1 is a horizontal sectional view taken through the heater; and Fig. 2 is a vertical sectional view of the same.

Similar reference characters refer to similar parts throughout both views of the drawings.

Referring now to the drawings, wherein I have shown my invention adapted to be applied to a hot water heating apparatus adapted to be used in railway cars or similar structures, 1 indicates a drum comprising in the present instance a chambered casting 2, a longitudinally extending casing 3 threaded into one end of casting 2, and a cap piece 4

threaded upon the opposite end of casing 3. Drum 1 is provided with ports, as at 5 and 6, either of which may be used as an inlet port, the one not so employed being adapted to be closed by means of a plug, and a water outlet port is provided for the opposite end of drum 1, as at 7. A suitable draw-off port is provided in drum 1 at 8 in the lowest portion thereof, through which the entire circulating system may be drained. It will be understood that water entering either of ports 5 or 6 will circulate through the drum 65 and leave the same through outlet port 7.

Threaded into the opposite end of casting 2 is a chambered head 9 provided with steam inlet ports, as at 10 and 11, either or both of which may be utilized for the admission of steam. A steam conduit 12 is threaded into head 9, said conduit extending longitudinally of water drum 1, the opposite end thereof being received in a suitable aperture 13 provided in the interior of head 4 and 75 closed by means of a screw plug 14.

Seated in an aperture of a web 15 which forms a wall of a chamber 16 into which lead the inlet ports 10 and 11 of head 9 is a spur tube 17. This tube, which is disposed 80 eccentrically with respect to conduit 12 so as to lie in the bottom thereof as shown in Fig. 2, extends longitudinally substantially the entire length thereof and is apertured, as at 18, so that the steam passing therethrough may freely enter said conduit. 85 Spur tube 17 is preferably formed of brass or similar metallic substance having a relatively high coefficient of expansion.

In the outer end of head 9 is formed a discharge port 19 which connects a valve chamber 20, the walls of which are integral with said head, with the interior of conduit 12 by means of a passageway 21. Extending through valve chamber 20 is a post 22, 95 one end of which is provided with a plurality of webs 23 which enter the discharge port 19, the dimensions of webs 23 being such as to center post 22 with respect to said port and also with respect to the walls of 100 valve chamber 20. Slidably mounted upon post 22 is a valve 24 adapted to coact with a valve seat 25 formed exteriorly of discharge port 19, valve 24 being normally urged toward said seat by means of a coil spring 26 105 encircling post 22 and interposed between

the valve and a collar 27 threaded upon the post and fixed in position thereon by means of a pin 27'. Threaded interiorly of post 22 and extending inwardly to the end of spur tube 17 is a stem 28, the inner end of which is secured to the corresponding end of the spur tube, stem 28 in the present instance being brazed thereto. Stem 28 is disposed eccentrically with respect to spur tube 17 and lies in contact with the bottom thereof, as clearly shown in Fig. 2 of the drawings. This stem is formed of a metal having a relatively low coefficient of expansion, in the present instance iron. Spur tube 17 and stem 28, being formed of metals having different coefficients of expansion, constitute a thermostatic device and control the opening and closing operations of valve 24 in accordance with the internal heat conditions of the heater.

In order to provide for a convenient adjustment of valve 24, the outer end of post 22, which is preferably squared as shown, enters a correspondingly shaped recess 29 in a plug 30 having a flange 31 which takes behind the inner walls of a nipple 32 threaded into the outer end of head 9. The outer end of plug 30 is squared or otherwise shaped to accommodate a wrench or other turning instrument, and is exteriorly threaded, as at 33, to receive a lock nut 34 which takes against the end of nipple 32 and thus holds the plug in fixed position. It will be understood that a loosening of lock nut 34 will allow plug 30 to be rotated, thereby rotating post 22 upon stem 28 to change the disposition of the valve 24 with respect to its seat.

Having thus described the construction of this embodiment of my invention, the operation thereof may now be understood. It will be understood that the circulating water flowing through the return pipe (not shown) of the heating system (not shown) and entering either of inlet ports 5 or 6 of drum 1 will circulate through said drum in contact with the exterior surface of steam conduit 12 to be heated by such contact by means of the steam within such conduit, and will flow out of said drum through the water outlet 7 to a feed pipe (not shown) of the circulating system. The steam entering through either of inlet ports 10 or 11 from the source of supply passes first into spur tube 17, and then enters the conduit 12 through the apertures 18 and through the partly open inner end of the tube. The water resulting from the condensation of the steam within conduit 12 flows rearwardly therethrough and is conducted to the discharge port 19 through passageway 21 which leads the same to valve 24, which by means of the relative expansion of spur tube 17 and stem 28 is opened or closed in accordance with the internal

heat conditions of the heater. The water of condensation then passes out of the heater through an outlet port which leads from valve chamber 20. It will be understood, of course, that valve 24 has been adjusted by means of plug 30 and post 22 to meet the particular conditions of the heating system in which the heater is employed.

It will accordingly be seen that I have provided a heating apparatus of the above type adapted to attain the several aims and objects of my invention in an exceedingly simple and efficient manner, and that by my construction the use of independent traps and similar contrivances for draining the steam conduits of heaters as hitherto constructed is entirely eliminated. Inasmuch as the spur tube and the valve stem are in direct contact with the steam and lie in the bottom of the steam conduit and in contact with any water of condensation contained therein, the thermostatic controlling means constituted by these parts is extremely sensitive in its operations. Owing to this feature of construction, the opening and closing movements of the valve respond quickly to differences in temperature of the circulating water, thus providing for the immediate entrance of a sufficient amount of steam into conduit 12 to impart the necessary amount of heat to the circulating water and for the discharge of the water of condensation from the conduit. It will also be apparent that valve 24 may be so adjusted, if desired, as to remain substantially closed until the water of the circulating system has reached a very low temperature, when the same will automatically open to permit the water of condensation to be discharged from the steam conduit, thus eliminating all danger of freezing.

The apparatus is constructed of comparatively few parts, and being self-contained can be constructed at a less cost than apparatus of this type as hitherto constructed, and at the same time it occupies less room beneath the car.

While I have shown my invention as adapted to be applied to water heating systems for railway cars, it will be understood that I do not wish to limit the same to such employment, nor in fact to any particular use, as the same is capable of being used advantageously in heating systems for other purposes, although the same is peculiarly adapted for use in the relation shown.

A modified form of the invention is described and claimed in my copending application, No. 379,327, filed June 17, 1907.

As many changes could be made in the above construction and many apparently widely different embodiments of this invention could be made without departing from the scope thereof, it is intended that

all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention which 10 as a matter of language might be said to fall therebetween.

Having described my invention, what I claim as new and desire to secure by Letters Patent is:

- 15 1. In a heater for a water circulating system, in combination, a water drum having water inlet and outlet ports, a steam conduit arranged to heat the water circulating through the water drum, a spur tube in said conduit for leading steam thereinto and a valve connected with said spur tube and controlled in accordance with the temperature thereof and positioned to drain the condensation water from said steam conduit.
- 20 2. In a heater for a water circulating system, in combination, a tubular member having water inlet and outlet ports, a second member located within said first-mentioned member comprising inner and outer tubes having respectively steam inlet and outlet ports, and means connected with said inner tube and controlled in accordance with the expansion thereof adapted to regulate the discharge from the outlet port of the said outer tube.
- 25 3. In a heater for a water circulating system, in combination, a water drum having water inlet and outlet ports, a steam conduit located therein having steam inlet and discharge ports, a valve for regulating the discharge from said steam conduit, and a thermostatic device for operating said valve comprising a tubular member having a relatively high coefficient of expansion secured at one end within said steam conduit and adapted to conduct steam therein, and a member having a relatively low coefficient of expansion located within said tubular member and secured to the opposite end thereof, said last mentioned member being connected with said valve.
- 30 4. In a heater for a water circulating system, in combination, a water drum having water inlet and outlet ports, a steam conduit located therein having steam inlet and discharge ports, a valve for regulating the discharge from said steam conduit, a tubular member of a relatively high coefficient of expansion secured at one end within said steam conduit to lead steam from said steam inlet port and eccentrically disposed within said conduit, and a member having a relatively low coefficient of expansion secured to the opposite end of said tubular member and connected with said valve, said tubular
- 35 member and said last mentioned member constituting a thermostatic device for opening and closing said valve.
5. In a heater for a water circulating system, in combination, a water drum having water inlet and outlet ports, a steam conduit located therein having steam inlet and discharge ports, a valve for controlling the flow from the discharge port of the steam conduit, and a thermostatic device for operating said valve comprising a spur tube of relatively high coefficient of expansion secured at one end within said steam conduit and adapted to conduct steam therein, and a rod of relatively low coefficient of expansion secured to the opposite end of said spur tube and connected with said valve. 70
6. In a heater for a water circulating system, in combination, a water drum having water inlet and outlet ports, a steam conduit located therein having steam inlet and discharge ports, a valve for regulating the flow from the discharge port of the steam conduit, and a thermostatic device for automatically operating said valve comprising a spur tube having a relatively high coefficient of expansion secured at one end in said steam conduit and in the avenue of flow of steam thereinto, said spur tube extending within said steam conduit and adapted to 80 discharge steam into the interior thereof, and a rod having a relatively low coefficient of expansion secured to the opposite end of said spur tube and connected with said valve. 85
7. In a heater for a water circulating system, in combination, a water drum having water inlet and outlet ports, a steam conduit having steam inlet and discharge ports, a valve arranged to regulate the flow from the discharge port of the steam conduit, and a thermostatic device for controlling said valve comprising a spur tube of a relatively high coefficient of expansion secured at one end within said steam conduit and 90 adapted to conduct steam to the interior thereof, said spur tube being eccentrically disposed therein and lying in the bottom thereof, and a rod having a relatively low coefficient of expansion secured to the opposite end of said spur tube and connected with said valve. 95
8. In a heater for a water circulating system, in combination, a water drum having water inlet and outlet ports, a steam conduit located therein having steam inlet and discharge ports, a valve for controlling the flow from the discharge port of the steam conduit, and a thermostatic device for operating said valve comprising a spur tube of 100 a relatively high coefficient of expansion secured in said steam conduit and lying in the bottom thereof, said spur tube being adapted to lead steam from said steam inlet and provided with a plurality of apertures 105
- 110
- 115
- 120
- 125
- 130

whereby steam is delivered to the interior of said steam conduit, and a rod having a relatively low coefficient of expansion attached to the inner end of said spur tube 5 and lying in the bottom thereof, said rod being connected with said valve.

9. In a heater for a water circulating system, in combination, a water drum having water inlet and outlet ports, a steam conduit 10 located therein having steam inlet and discharge ports, a valve chamber located adjacent the discharge port of the steam conduit, a post located in said valve chamber, said post being provided with centering 15 webs extending within said discharge port, a valve loosely mounted upon said post and covering said discharge port, a spur tube having a relatively high coefficient of expansion located within said steam conduit 20 and seated at one end in said steam inlet port, and a stem having a relatively low coefficient of expansion secured to the opposite end of said spur tube and adjustably attached to said post.

25 10. In a heater for a water circulating system, in combination, a water drum having water inlet and outlet ports, a steam conduit located therein having steam inlet and discharge ports, a valve chamber arranged 30 adjacent the discharge port of the steam conduit, a post located therein having centering webs extending within said discharge port, a valve loosely mounted upon said post, a spur tube having a relatively high coefficient of expansion extending 35 within said steam conduit and connected to lead steam from said steam inlet port into said steam conduit, and a stem having a relatively low coefficient of expansion secured 40 to the inner end of said spur tube and having a threaded engagement with said post.

11. In a heater for a water circulating system, in combination, a water drum having water inlet and outlet ports, a steam conduit 45 located therein having steam inlet and discharge ports, a valve chamber arranged adjacent the discharge port of the steam conduit, a post located in the said valve chamber and centered with respect to 50 the said discharge port, a valve loosely mounted upon said post, a thermostatic device for operating said valve comprising a spur tube having a relatively high coefficient of expansion located within said steam conduit and having one end thereof connected 55 to lead steam from said steam inlet port into said conduit, a stem having a relatively low coefficient of expansion fixed to the other end of said spur tube and having a threaded connection with said post, and a member 60 having a sliding but non-rotatable engagement with said post adapted to adjust the same upon said stem.

12. In a heater for a water circulating system, in combination, a water drum hav-

ing water inlet and outlet ports, a steam conduit located therein having steam inlet and discharge ports, a valve chamber arranged adjacent the discharge port of the steam conduit, a post located in the said valve chamber and centered with respect to 70 the said discharge port, a valve loosely mounted upon said post, a thermostatic device for operating said valve comprising a spur tube having a relatively high coefficient 75 of expansion located within said steam conduit and fixed at one end in operative relation to said steam inlet port, a stem having a relatively low coefficient of expansion fixed to the free end of said spur tube and having a threaded connection with said post, and means for adjusting said valve 80 from the exterior of said steam conduit.

13. In a heater for a water circulating system, in combination, a water drum having water inlet and outlet ports located at opposite ends thereof, a steam conduit located therein having steam inlet and discharge ports, a valve chamber arranged adjacent the discharge port of the steam conduit, a post located in the said valve chamber and centered with respect to the said discharge port, a valve loosely seated upon 85 said post, a collar fixed upon said post, a spring interposed between said collar and said valve whereby said valve is urged in the direction of said discharge port, a spur tube leading from the inlet port of the steam conduit to the interior thereof, said spur tube being formed of a metal of a relatively high coefficient of expansion, a stem secured to the inner end of said spur tube having a threaded engagement with said post, said stem being formed of a metal 90 having a relatively low coefficient of expansion, and means for adjusting said post 95 upon said stem to change the position of the valve with respect to the discharge port of the steam conduit.

14. In a heater for a water circulating system, in combination, a water drum having water inlet and outlet ports located at opposite ends thereof, a steam conduit located therein having steam inlet and discharge ports, a valve chamber arranged adjacent the discharge port of the steam conduit, a post located in the said valve chamber and centered with respect to the said discharge port, a valve loosely seated upon 110 said post, a collar fixed upon said post, a spring interposed between said collar and said valve whereby said valve is urged in the direction of said discharge port, a spur tube leading from the inlet port of the steam conduit to the interior thereof, said spur tube being formed of a metal of a relatively high coefficient of expansion, a stem secured to the inner end of said spur tube having a threaded engagement with said 115 post, said stem being formed of a metal 120 having a relatively low coefficient of expansion, and means for adjusting said post upon said stem to change the position of the valve with respect to the discharge port of the steam conduit.

15. In a heater for a water circulating system, in combination, a water drum having water inlet and outlet ports located at opposite ends thereof, a steam conduit located therein having steam inlet and discharge ports, a valve chamber arranged adjacent the discharge port of the steam conduit, a post located in the said valve chamber and centered with respect to the said discharge port, a valve loosely seated upon 125 said post, a collar fixed upon said post, a spring interposed between said collar and said valve whereby said valve is urged in the direction of said discharge port, a spur tube leading from the inlet port of the steam conduit to the interior thereof, said spur tube being formed of a metal of a relatively high coefficient of expansion, a stem secured to the inner end of said spur tube having a threaded engagement with said post, said stem being formed of a metal hav-

ing a relatively low coefficient of expansion, and a member capable of rotation from the exterior of said steam conduit having a sliding but non-rotatable engagement with said 5 post adapted to rotate the same, whereby the valve is adjusted upon said stem.

15. In a heater for a water circulating system, in combination, a water drum having water inlet and outlet ports located at opposite 10 ends thereof, a steam conduit located therein having steam inlet and discharge ports, a valve chamber arranged adjacent the discharge port of the steam conduit, a post located in the said valve chamber and centered with respect to the said discharge port, a valve loosely seated upon said post, a collar fixed upon said post, a spring interposed between said collar and said valve whereby said valve is urged in the direction 15 of said discharge port, a spur tube leading from the inlet port of the steam conduit to the interior thereof, said spur tube being formed of a metal of a relatively high coefficient of expansion, a stem secured to the 20 inner end of said spur tube having a threaded engagement with said post, said stem being formed of a metal having a relatively low coefficient of expansion, a member capable of rotation from the exterior of said 25 steam conduit having a sliding but non-rotatable engagement with said post adapted to rotate the same, whereby the valve is adjusted upon said stem, and a lock-nut 30 threaded upon said adjusting member adapted to hold the same in fixed position.

16. In apparatus of the nature described, in combination, a water circulating system adapted to serve as a source of heat, a steam conduit adapted to heat the water in said 40 system, a spur tube secured to one end and extending within said conduit adapted to conduct steam therein, a valve controlling the discharge of condensation water from said conduit, and a connection between said 45 valve and the free end of said tube whereby said valve is controlled in accordance with the expansion of said tube.

17. In apparatus of the nature described, in combination, a tube positioned to act as 50 a heating element, a spur tube mounted at one end and extending throughout its length within said first tube and adapted to lead steam into the same, a valve controlling the discharge of water of condensation from 55 said first tube, and an operative connection between said valve and the free end of said

second tube whereby said valve is controlled in accordance with the expansion of said second tube.

18. In apparatus of the nature described, 60 in combination, a tube positioned to act as a heating element, a spur tube mounted at one end and extending throughout its length within said first tube and adapted to lead steam into the same, a valve controlling the 65 discharge of water of condensation from said first tube, a connection between said valve and the opposite end of said second tube whereby said valve is controlled in accordance with the expansion of said second 70 tube, and a water circulating system comprising means adapted to lead water into contact with the outer surface of said first tube to derive heat therefrom.

19. In a heating system, in combination, a 75 casing having feed and discharge passages therein, a valve located therein adapted to control the discharge from said casing, a spur pipe connected with said feed passage, a steam conduit connected 80 with said discharge passage and surrounding said spur pipe, and means secured interiorly of said spur pipe and connected with said valve, said spur pipe and said means constituting a thermostatic device 85 adapted to control the operation of said valve in accordance with the internal heat conditions of the system.

20. In a heating system, in combination, a steam conduit having feed and discharge 90 ports, a valve seat provided upon the discharge port, a valve coacting therewith, a thermostatic device for controlling said valve comprising a spur tube of a relatively high coefficient of expansion lying within 95 said steam conduit upon the bottom thereof, and having connection at one end with said feed port, and a rod having a relatively low coefficient of expansion secured to the opposite end of said spur tube and adjustably 100 connected with said valve, said spur tube and said rod constituting a thermostatic device adapted to control the operation of said discharge valve in accordance with the internal heat conditions of the system. 105

In testimony whereof I affix my signature, in the presence of two witnesses.

ROBERT M. DIXON.
